UNITED STATES PATENT OFFICE.

HARRY S. STORMER, OF JOHNSTOWN, PENNSYLVANIA.

BOILER TUBE AND FLUE CLEANER.

949,637.

Specification of Letters Patent. Patented Feb. 15, 1910.

Application filed April 7, 1908. Serial No. 425,730.

To all whom it may concern:

Be it known that I, HARRY S. STORMER, a citizen of the United States, residing at Johnstown, in the county of Cambria and 5 State of Pennsylvania, have invented new and useful Improvements in Boiler Tube and Flue Cleaners, of which the following is a specification.

This invention relates to boiler tube and 10 flue cleaners, and more particularly to that class of cleaners comprising a rotary motor actuated by a suitable pressure medium fed through a hollow tube or pipe connected to the cleaner and serving as a handle for manipulating the cleaner while in operation.

The present invention is an improvement of the construction disclosed by my Patent No. 874,258, dated December 17, 1907, and embodies a different type of motor and a 20 cleaning head rotatably associated with the remaining mechanism by means of modified connecting devices but embodying a ball and socket joint and operating by a pounding action as well as penetration to loosen and 25 move scale or other material adhering to the interior of a tube or flue in a manner similar to the operation described in my patent. In the present instance the construction is 30 very much simplified and is stronger and more durable than the construction covered by my patent and any part can be replaced at a small cost.

In the improved structure the several parts are so constructed and arranged as to 35 perfectly line up with one setting and the front working extremity or mechanism is so constituted that any part thereof may be replaced by anyone, whether skilled in mechanical structure or not, and, further, this 40 advanced working mechanism is advantageous in that it does not embody in its organization small fastening screws or pins which are liable to shear off or break.

Other advantageous structural details will 45 be hereinafter more fully explained.

In the drawings: Figure 1 is a longitudinal vertical section of a tube or flue cleaner embodying the features of the invention. Fig. 2 is a transverse vertical section on the 50 line 2—2, Fig. 1. Fig. 3 is a transverse vertical section on the line 3—3, Fig. 1. Fig. 4 is a transverse vertical section on the line 4—4, Fig. 1. Fig. 5 is a transverse vertical section on the line 5—5, Fig. 1. Fig. 6 is a 55 perspective view of the parts of the motor

shown separated. Fig. 7 is a perspective view of the parts of the working mechanism in advance of the motor and also shown separated.

Similar characters of reference are employed to indicate corresponding parts in the several views.

The main body of the cleaner comprises a cylindrical casing 1 having the opposite extremities interiorly screw-threaded to receive rear and front caps 2 and 3. The rear cap 2 is flared or cupped to provide a chamber 4 for the reception and distribution of a pressure medium which is fed into said chamber through a tube or pipe 5 of any suitable form centrally secured to the cap and which may be of any suitable length and serve as a handle for manipulating the cleaner. The front closing cap 3 has its connected extremity similarly flared and cupped to provide an exhaust chamber 6 and is also formed with a plurality of exhaust openings 7, both caps 2 and 3 having suitable angular wrench-engaging projections 8 for applying and removing the same in relation to the cylindrical casing 1. The front cap 3 has a central opening 9 therein through which projects the front extremity of a rotary shaft or axle 10 continuous with a rotary piston 11 mounted in and coöperating 75 with a cylinder 12 which is forced into the casing 1 by pressure and is formed with an eccentric bore 13, see Fig. 4, extending therethrough from end to end. The cylinder 12 is engaged at opposite extremities by bronze 90 bearings 14 and 15, the front bearing 15 being provided with an exhaust opening 16 and a smaller opening 17 to receive a dowel pin 18 projecting from the adjacent end of the cylinder 12. The bearing 14 is 95 formed with an inlet port or opening 19 and a smaller opening 20 to receive a dowel pin 21 on the adjacent end of the cylinder 12, and both bearings are centrally counterbored as at 22 to receive shouldered portions 23 of the rotary piston to hold the latter in accurate operating position with 100 relation to the cylinder 12. Each bearing is also formed with a peripheral seat 24 at its inner portion to receive a flange 25 on the adjacent end of the cylinder 12 to insure the formation of a tight joint at each end of the cylinder or motor by instituting a snug fitting between the bearings and the cylinder ends. The front bearing 15 has a 110

forwardly projecting integral sleeve 26 through which the shaft or axle 10 rotatably projects, and the rear bearing 14 has a rearwardly projecting cap 27 extending into the chamber 4 and closing over the rear extremity of the rotary piston 11 which is reduced and fits within the said cap. The portions of the rotary piston engaging the sleeve 26 and the cap 27 may be termed 10 journals for the said piston and with the counterbores 22 serve to maintain the piston in proper position within the cylinder 12. The inlet port 19 in the bearing 14 communicates with a passage or inlet groove 28 in the rear end of the cylinder 12, and the exhaust or outlet opening 16 likewise registers with an outlet passage or groove 29, the inlet port 19 being of less diameter than the outlet opening or port 16, so that the 15 exhaust may be quickly liberated through the said opening or port 16. The rotary piston 11 is equipped with a pair of radially movable blades or wings 30 and 31 having their inner opposing edges movably assembled and reversely cut away, as at 32, to provide a flush break joint, and the inner portions of the blades or wings are also transversely bored as at 33 to receive expelling springs 34 tending to normally force the blades 30 and 31 outwardly and maintain the ends of the said blades in continual contact with the eccentric bore or piston chamber 13. The piston 11 is of materially less diameter than the bore or chamber 13 and 20 consequently the blades or wings 30 and 31 are permitted to alternately move inwardly and outwardly with respect to the piston, as will be readily understood. The front extremity or terminal 35 of the shaft or axle 10 which projects continuously from the rotary piston 11 or forms an integral part of the latter is reduced and formed with a flattened surface 36, or angular in cross-section to receive a wrench for holding the said shaft or axle when applying the advance 25 working mechanism thereto or when removing said mechanism, and said reduced extremity of the shaft or axle is also exteriorly screw-threaded for coupling purposes, as will be presently explained.

The advance working or scale and sediment loosening mechanism comprises a socket member 37 secured to the front reduced extremity of the shaft or axle 10 by a coupling device or sleeve 38 which is suitably interiorly and exteriorly screw-threaded to engage the front extremity of the shaft and fit within the rear extremity of the socket member 37, the said coupling device or sleeve 38 having 30 a circumferential flange 39 against which the rear end of the socket member has bearing when the attachment of these parts is completed. The socket member 37 has an elongated bore 40 therethrough or is 35 tubular, and the front extremity of the bore

is regularly contracted in the arc of a circle, as at 41, and the front extremity of the socket member has the edge around the bore removed or cut away in a concaved plane, as at 42, to give a clearance for a swinging 40 part, which will be presently explained. The flange 39 of the coupling device 38 is provided with wrench engaging faces 43, as shown by Fig. 7, and the advance working mechanism, which is connected to the 45 socket member 37 may be simultaneously applied with the said socket to the front reduced extremity of the shaft or axle 10 or similarly removed from the said shaft extremity. The socket member 37 is circumferentially grooved as at 44 and is also formed with a diametrically extending opening 45 to removably receive a coupling key or pin 46 having one end formed with a recess or cavity 47. A removable spring 50 keeper 48, consisting of a resilient band, is secured in the groove 44, and is provided with an inwardly extending projection 49 to engage the recess or cavity 47 of the coupling key or pin 46. It will be seen that the 55 keeper 48 prevents the pin 46 from becoming accidentally disengaged or slipping out of the socket member 37, and the diametrically extending opening 45 in which the pin 46 is removably seated may at times be 60 used, when the pin is removed, for introducing suitable lubricating material into the socket member 37. The keeper 48, when applied to the socket member 37, has its outer surface flush with the adjacent surface of the 65 said member so as to avoid formation of interfering projections that would soon become worn and detract from the usefulness and function of the said keeper. The socket member 37 is engaged by a spherical or 70 ball head 50 having a central stem 51 projecting therefrom and terminally screw-threaded. A slot 52 is formed in and extends diametrically through the head 50 and opens fully also through the rear extremity 75 of the said head, the opening 52 having a transverse extent sufficient to permit the key or pin 46 to be inserted therethrough and readily removed from the head. The front wall 53 of the slot 52 is convex so as 80 to permit the head to roll or move in opposite lateral directions on the key or pin 46. The key or pin 46 prevents the head 50 from turning in the socket and moving rearwardly beyond a predetermined point, and 85 the rear portion of the said head is cut away as at 54 to clear the forward extremity of the coupling sleeve 38 and thus avoid the least restriction to the movement of the said head, or to provide a universally movable connection which is separably attached to the shaft. 90 Loosely interlocked eye members 55 and 56 of eye-connecting bolts 57 and 58 are attached to the spherical head 50, the eye bolt 57 having a rearwardly projecting 95 100

screw-threaded shank 59 which is connected to the stem 51 of the head 50 by a coupling sleeve 60 having outer wrench-engaging faces 61 at the center, the threads on the 5 stem 51 and shank 59 being so disposed as to facilitate the drawing together or assemblage of the said stem and shank and to resist accidental loosening movement. The eye bolt 58 has a forwardly projecting 10 screw-threaded shank 62 connected to the central portion of the rear end of a cleaning head 63, the latter being preferably of conical form, as shown, and presenting a conically curved working surface with cutting 15 ribs 64 projecting therefrom at intervals provided with angular edges 65 to facilitate loosening and removal of scale or sediment from the interior of tubes or flues. Each rib 64 presents one cutting edge 65, and the 20 spaces between the ribs serve as clearance means for the loosened scale or sediment. The ribs 64 taper equally with the remaining portion of the cleaning head from the rear extremity toward the front end of the 25 latter and such form of head will be found exceptionally efficient in performing the function for which it has been devised.

From the foregoing it will be seen that all the parts of the cleaner may be readily 30 dissociated and assembled, and in the event that any part becomes worn and unfit for use or broken it may be readily replaced at a minimum cost and without interfering with the operation of the remaining parts 35 which may still be in good working order. Furthermore, it will be observed that the use of small connecting devices or means liable to become broken or displaced is avoided, with advantages in the prolonged 40 use or durability of the complete cleaner.

Any motive fluid may be used for operating the cleaner, such, for instance, as air or steam, and this fluid is admitted into the chamber 4 and from the latter passes 45 through the opening or port 19 into the piston chamber or bore 13 and successively expands against the blades or wings 30 and 31 and thus rotates the piston 11, the fluid finally exhausting through the opening or 50 outlet port 16 into the chamber 6 and escapes through the opening 7 into the tube or flue being cleaned, with advantages in assisting in the cleaning operation or facilitating loosening of the scale or sediment adhering 55 to the interior of the tube or flue. The rotation of the piston 11 is directly transmitted to the shaft or axle 10 without the least lost motion and from the said shaft or axle 10 the advance working or cleaning mechanism is similarly rotated and at the same time the cleaning head 63 is thrown laterally in opposite directions with a pounding action against the inner wall of the tube or flue with considerable force and at the same time 60 that the said head is rotated. This opera-

tion of the cleaning head 63 will result in an expeditious loosening of the scale or sediment, and as the head is continually changing its angular position the interior portion of the tube or flue will be fully engaged and at the same time the exhaust motive fluid will forcefully drive the loosened material ahead or in advance of the mechanism and materially aid in preventing the cleaning head 63 from becoming clogged as well as 70 obstruct the backward movement of the removed scale or sediment and penetration thereof into the working parts, though the joints between the several parts are all so tight as to avoid entrance therein of any of the removed sediment under normal conditions. The bounding action of the cleaning head 63 regularly from one position to another with respect to the interior of the tube or flue will break the scale or sediment in 75 pieces instead of grinding it and thus thoroughly clean the tube or flue.

Oil ducts 66 and 67 are provided in the rear extremity of the motor and the shaft 10 respectively and communicate with the 80 wings 30 and 31 centrally disposed in the motor or piston, and at other points oil ducts may be provided where necessary to keep the several parts well lubricated, it being required to thoroughly lubricate the cleaner 85 after each use or cleaning operation, or when the cleaner has completed the removal of scale or sediment from the tube or flue. The ducts 66 and 67 communicate with the slot in the piston 11 in which the wings 30 and 90 31 are mounted and have movement in order to ease the operation of the said wings, as will be readily understood. It will be observed that the shaft or axle 10 is continuous with the rotary piston and directly transmits the 95 rotary movement of said shaft to the advance working or scale and sediment removing mechanism. As in my patent hereinbefore mentioned, the ball and socket connection between the shaft and axle and the 100 cleaning head 63 is advantageous, and in addition the engaged eye-bolts forming a universal joint connection renders the cleaning head 63 very sensitive and effective in its 105 operation.

It will be understood that changes in the proportions, dimensions and minor details may be resorted to or adopted without departing from the spirit of the invention.

Having thus fully described the invention, 120 what is claimed as new, is:

1. In a tube or flue cleaner, a motor means having a shaft rotatably projecting therefrom, a ball and socket joint separately attached to the projecting extremity of the shaft, a cutter head having a link connecting means carried thereby and forming a universal joint, and means separately engaging a portion of the link connecting means and the ball of the said ball and socket joint 125 130

- whereby the ball and socket joint and the link connecting means with the cutter may as a whole be detached from the shaft or the link connecting means and cutter disconnected from the ball and socket joint.
2. In a tube or flue cleaner, a motor means having a shaft rotatably projecting therefrom, a ball and socket joint separably attached to the projecting extremity of the shaft, a cutter head, a loose link connection attached to the cutter head, and a coupling means detachably connecting the ball of the ball and socket joint and a portion of the loose link connection.
- 15 3. In a tube or flue cleaner, a motor means having a shaft rotatably projecting therefrom, a universal joint separably attached to the projecting extremity of the shaft, a cutter head, a loose link connection attached 20 to the cutter head, and a coupling means detachably connecting the movable portion of the universal joint and a part of the said loose link connection.
4. In a tube or flue cleaner, a motor means 25 having a shaft rotatably projected therefrom, a socket detachably connected to the projected portion of the shaft and having a transverse opening, a slotted spherical head mounted in the socket and having a forwardly projecting stem, a pin removably engaging the socket and slotted spherical head, a resilient band fitted on the socket and having a portion engaging one end of the pin, a cutter head, and a loose link connection in- 30
- terposed between the cutter head and the stem of the spherical head.
5. In a tube or flue cleaner, a motor means having a shaft rotatably projecting therefrom, a socket member detachably connected to the projecting extremity of said shaft, a coupling sleeve interposed between the socket member and extremity of the shaft, a slotted spherical head mounted in the socket member and having a forwardly projecting stem, means detachably connecting the spherical head from the socket member, a cutter head, and a loose link connection in part fixed to the cutter head and having the remaining portion detachably connected to the stem of the spherical head. 50
6. In a tube or flue cleaner, a motor means having a shaft rotatably projecting therefrom, a socket member separably attached to the projecting extremity of the shaft, a spherical head loosely mounted in the 55 socket member and having a forwardly projecting stem, a cutter head, a loose link connection attached to the cutter head, and a coupling sleeve detachably connecting the stem of the spherical head and one of the 60 links of the loose link connection.

In testimony whereof I have hereunto set my hand in presence of two subscribing witnesses.

HARRY S. STORMER.
